UNITED STATES PATENT OFFICE.

ARTHUR PERRIN, OF NEW LISKEARD, ONTARIO, CANADA.

TABLE LOCK.

Application filed May 16, 1922. Serial No. 561,369.

To all whom it may concern:

Be it known that I, ARTHUR PERRIN, a subject of the King of Great Britain, and resident of the town of New Liskeard, in the Province of Ontario, Dominion of Canada, have invented certain new and useful Improvements in Table Locks, of which the following is a specification.

This invention relates to improvements in table locks and more particularly to locks for extension tables.

The objects of the invention are to provide a simple, economical and effective device of this kind for extension tables whereby on the table being extended to receive one or more leaves, the whole may be securely held and locked together and as readily released or unlocked when desired.

With the foregoing and other objects in view, the invention consists essentially of a guiding member suitably notched to fit on one section of an extension table and a locking member adapted to slidably engage the guide member to fit on the other table section, and means for operating the locking member.

Referring to the drawings, in which like characters of reference indicate corresponding parts in each figure.

Figure 1 is a side elevation of an extension table fitted with my invention.

Figure 2 is a perspective view of the table lock detached from the table, and

Figure 3 is a cross sectional view on line 3—3, of Figure 2.

In the drawings;

A is the lock or device as a whole and B is an ordinary extension table comprising two sections C and D, with the lock A fitted thereon. This lock A comprises, as here illustrated, an L shaped metal strip or guide member 10 including a side 11 and base 12 formed with a guiding edge 13 and designed to be fitted and fixedly secured on the side of one of the table sections and to be securely held there by suitable retaining means through the orifice 14. 15 are notches suitably spaced to correspond with the width of the extra table leaves and adapted to engage with the locking member. This member is securely fitted on the other section C of the table A and comprises a locking bar 16 formed with a looped end 17 adapted

to engage and lock with the notches 15. The other end of the locking bar 16 is formed with a bend adjacent to the end thereof while the end itself is bent inwardly to engage with a crank member 18 provided with a handle 18^a and pivotally mounted on a plate 19 in turn mounted on the table section C. 20 is an intermediate support for the bar 16 between the operating end and the guide member 10 and is preferably mounted on the same section of the extension table as the locking member. The member 20 is provided with a slot for receiving the rod 16 therethrough and made sufficiently larger than the rod to permit vertical movement of the latter therein. 21 is the bend previously referred to in the bar 16 whereby in combination with the operating crank 18 and the guide 20, the locking end 17 of the locking bar 16 is operated to lock with the notches 15. 22 is a combined guard and guide plate fixedly secured on the bar 16 and designed to slidably engage with the ridge 13 on a guide member 10 to retain the bar in place on said guide member.

From the foregoing, it will be evident that upon the movement of the crank 18 the bar 16 will be shifted to engage or disengage the hook end 17 with the slots 15 to lock or unlock the bar 16 dependent upon the direction of crank movement, the notches 15 being spaced preferably according to the width of the leaves of the table.

If two leaves are put in, the locking bar engaging point will be opposite the second notch to be there locked by the operating crank handle.

As many changes could be made in the above construction, and many apparently widely different embodiments of my invention, within the scope of the claim, constructed without departing from the spirit or scope thereof, it is intended that all matter contained in the accompanying specification and drawings shall be interpreted as illustrative and not in a limiting sense.

What I claim as my invention is:

A table lock of the character described, comprising a plate adapted to be attached to one section of the table and presenting a horizontal portion formed with a series of longitudinally spaced notches, a crank pivoted at one end to another section of the

table, a locking rod rigidly secured at one end to an intermediate portion of the crank and equipped at its opposite end with means adapted to engage and disengage the notches of the said plate upon tilting of the locking rod in response to pivotal movement of the crank and a bracket provided with a slot loosely receiving the intermediate portion of the rod therethrough, said brackets serv-

ing to limit upward and downward tilting 10 of the rod.

In witness whereof I have hereunto set my hand in the presence of two witnesses.

ARTHUR PERRIN.
